(57) **CLAIM**

The ornamental design for a camera pole mount, as shown and described.

DESCRIPTION

FIG. 1 is a front, top, and right side perspective view of a camera pole mount;

FIG. 2 is a rear, bottom, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, top, and right side enlarged perspective view of the encircled area labeled “9” in FIG. 1; and,

FIG. 10 is a rear, bottom, and left side enlarged perspective view of the encircled area labeled “10” in FIG. 2.

The broken lines in the drawings are included for the purpose of illustrating environmental structure and form no part of the claimed design.

1 Claim, 10 Drawing Sheets
